UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-DRAWING BLOCK.

SPECIFICATION forming part of Letters Patent No. 729,541, dated June 2, 1903.

Application filed July 8, 1902. Serial No. 114,783. (No model.)

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Drawing Blocks, of which the following is a specification, accompanied by drawings forming a part of the same, in which—

10 Figure 1 is a longitudinal section on line 1 1 of Fig. 3. Fig. 2 is a similar section on line 2 2 of Fig. 3. Fig. 3 is an end view. Fig. 4 is a plan view showing the application of the wire-drawing blocks to a machine for 15 giving them motion, and Fig. 5 is an end view of the same.

Similar reference-figures refer to similar parts in the different views.

The object is to provide a movable grip to 20 which the end of the wire is attached, fastened to the block in such a manner that it recedes from the flange as the wire is wound upon the block between it and the flange, thus preventing the wire as it is drawn 25 through the die and wound upon the block from bunching up upon the block.

Referring to the accompanying drawings, 1 denotes the block, and 2 is the block-shaft, on each end of which a block is secured. The 30 blocks are both alike, and only one will be described. The block 1 is loosely mounted on a spindle 3 and is adapted to be locked to the shaft by means of the spring-actuated pin 4, which has sliding connection with the block, 35 having a handle 5 at its outer end, by which it is manipulated, and a block at its inner end adapted to enter an orifice 6, formed to receive it in the collar 7, keyed on the shaft 2. The general form of the block is tapering, it having 40 the usual flange 8 at its inner end and being for the most part hollow. The rod 9 extends throughout a portion of the length of the block, and the cross-bar 10 has pivotal sliding connection with this rod at one of its ends, 45 the opposite end 11 of said bar traveling in contact with a wear-plate 12, of hardened steel, as there is considerable pressure in friction at that point. A link 13 is hinged to the free end of the cross-bar 10, and pivotally connected with the outer end of said link

is a wire-grip 14, said grip having the usual jaws therein between which to receive the end of the wire and hold it while the wire is being drawn through the die. There is a die of course for each block, and in the construction of the machine illustrated the die-boxes 15 15 are pivoted at 16 16 to the table 17 of the machine and have a joint 18 to allow them to swing upwardly, so that freedom of movement to the dies is afforded. Shaft 2 is driven 60 in any approved manner—as, for instance, through the gearing shown in Figs. 4 and 5, in which a large gear-wheel 19 is keyed or otherwise secured to the shaft. A main drive-shaft 20 and counter-shaft 21 are arranged 65 parallel with the block-shaft 2, and these shafts are provided with small and large gear-wheels 22 and 23, respectively, intermeshed with each other, and shaft 21 is provided with a small pinion 24, which meshes with the 70 teeth of gear-wheel 19, power being applied through pulley 25. In this way the desired relative speed of the drive or pulley shaft 20 and the blocks 1 1 is provided for.

In operation the end of the wire is clamped 75 in the grip in the usual manner, the cross-bar 10 being slid up as near the flange 8 on the block as it will go. The machinery is set in motion and the wire winds upon the drum close up against the flange, crowding the movable bar 10 with its grip outward on the block by striking against the lug 10^a on one end and the link 13 at the other, as shown in Fig. 2, the grip holding the end of the wire all the while and receding as fast as more wire is 85 crowded between the coils formed and the flange 8 until the block has attained its full complement of wire, when the wire is disposed of in the usual manner.

What I claim as my invention, and desire 90 to secure by Letters Patent, is—

1. A wire-drawing block having a flange and a sliding grip mounted to slide axially on the drawing-block to which an end of the wire being drawn is secured, and between 95 which grip and the flange on the end of the block the wire is crowded as the successive coils are wound upon the block, substantially as described.

2. A wire-drawing block having a flange 100

and a sliding grip mounted to slide axially on the drawing-block to which an end of the wire being drawn is secured, and between which grip and the flange on the end of the block the wire is crowded as the successive coils are wound upon the block, and a wear-plate against which the free end of the grip slides, substantially as described.

3. A wire-drawing block having a flange at one end, a movable bar, and a grip having a pivotal connection with said bar and between which and said flange the wire is coiled, substantially as described.

4. The combination with a wire-drawing block, of a cross-bar having at one end a pivotal and sliding connection with said block, and a wire-grip pivoted to the opposite end of said cross-bar being arranged to be crowded by the wire as it is wound on said block in a direction parallel with the axis of the block, substantially as described.

5. A wire-drawing block having a rod ex-

tending substantially throughout its length, a cross-bar having pivotal sliding connection on said rod, and carrying a lug or projection at one end which extends beyond the surface of the block, and a wear-plate against which the free end of the bar slides, and means for connecting an end of the wire to the cross-bar, substantially as described.

6. A wire-drawing block having a rod and wear-plate extending longitudinally thereof, said parts removed some distance from each other, a cross-bar having pivotal sliding connection with the rod and bearing upon the wear-plate, said rod having an outwardly-extending lug at one end, a link pivoted to the other end, and a grip pivoted to the link, substantially as described.

Dated this 1st day of July, 1902.
